UNITED STATES PATENT OFFICE

RALSTON SMITH, OF OAKLAND, CALIFORNIA

ICE SHAVING MACHINE

Application filed July 31, 1929. Serial No. 382,340.

This invention relates to ice shaving or grinding machines for use in shaving ice in the production of a confection which is commercially known as "snow cone." This confection is produced by filling a paper cone with ground ice and applying a flavoring syrup thereto.

It is the principal object of the present invention to provide a simple and effective machine to which pieces of ice may be delivered and which is operative to rapidly grind the ice into finely divided particles and deliver the same into a dispensing cylinder for convenient insertion into a paper cone.

One form which the invention may assume is exemplified in the following description and illustrated by way of example in the accompanying drawing, in which:

20 Fig. 1 is a view in side elevation of the machine.

Fig. 2 is a central vertical section through the same.

25 Fig. 3 is a plan section taken on line III—III of Fig. 2.

Fig. 4 is a plan section taken on line IV—IV of Fig. 2.

Referring more particularly to the accompanying drawing, 10 indicates an ice grinding machine formed of a vertical cylinder 11 having a supporting base 11a. The upper end of the cylinder 11 is enlarged and constitutes a hopper 14 into which pieces of ice may be inserted.

35 At one side of the cylinder 11 its wall is formed with a vertical slot 15 which forms a communicating passageway between the grinding cylinder 11 and a dispensing cylinder 12. The dispensing cylinder is formed integral with the grinding cylinder in alignment with the slot 15. A grinding blade 17 is arranged in the slot at one side thereof and its cutting edge projects a slight distance within the grinding cylinder 11.

40 Arranged within the cylinder 11 is a cone 18 which is secured on a shaft 19 rotatably supported concentrically of the cylinder 11.

The cone 18 has a base of a diameter substantially agreeing with the interior diameter 50 of the cylinder 11. The base of the cone 18

is disposed contiguous to the bottom of the cylinder 11.

Formed on the surface of the cone 18 is a helical feeding blade 20. This blade is for the purpose of rotating the ice on the cylinder and feeding the particles thereof downwardly over the blade 17.

When the machine is in operation the cone 18 is revolved continuously so that the ice in the cylinder 11 will be revolved and pass over the blade 17. The cone 18 serves to maintain the ice at the perimeter of the cylinder as it is reduced and the helical blade 20 causes the ice to revolve as it is fed downwardly over the grinding blade 17.

To revolve the cone 18 the shaft 19 is fitted with a worm gear 21 which is in mesh with a worm 22 secured on a shaft 23. This shaft is adapted to be driven by an electric motor 24 through the medium of a clutch 25. This clutch is engaged and disengaged by means of a lever arrangement 26 so that the motor may be continuously operated while enabling the machine to be placed in operation only at desired periods.

In forming the "snow cone" it is desirable that the ice be molded in the shape of a cone at the top of the cone. I accomplish this by providing a hollow conical plunger 27 in the dispensing cylinder 12. This cone shaped plunger is fitted with an operating member 28 which is vertically reciprocable in a slot 29 formed vertically of the dispensing cylinder 12. The conical plunger 27 is connected by a light tension spring 30 to the top of the dispensing cylinder 12. This spring is for the purpose of returning the plunger 27 to its uppermost position after it has been moved downwardly to dispense the ice from the dispensing cylinder.

In operation of the machine, the cover 31 of the hopper 14 is opened and the hopper and cylinder 11 are filled with pieces of ice. The clutch 25 is then engaged which causes the cone 18 and the blade 20 thereon to revolve. As the ice is revolved over the blade 17 it will be shaved or ground and the ground particles or shavings will pass through the slot 15 into the dispensing chamber. During this time a paper cone such as indicated by

the numeral 32 is held under the open lower end of the dispensing chamber 12 by the operator.

As the ice in the cylinder 11 becomes reduced it will be maintained in contact with the blade 17 by the tapered walls of the cone 18 and will be forced downwardly and be revolved by means of the helical blade 20.

When sufficient ground or shaved ice has been delivered to the dispensing cylinder 12, the operating member 28 of the plunger 27 is depressed causing the plunger 27 to move downwardly packing the ice in the cone 32 and molding the ice at the upper end of the cone to a conical shape. The operating member 28 is then released and the spring 30 returns the plunger 27 to its uppermost position. A flavoring syrup is then added to the ice in the cone and the confection is formed.

From the foregoing it is obvious that I have provided a very simple and efficient machine for shaving or grinding ice and assisting in the production of what is known as "snow cone".

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

35. 1. A machine of the character described comprising a cylinder, a hopper formed at the upper end of the cylinder and into which pieces of ice may be deposited, said cylinder having a vertical slot formed in the wall thereof, a cone arranged concentrically of the cylinder in alignment with the slot, a vertical blade secured to the cylinder at one side of the slot and having a sharpened edge projecting into the cylinder, said cone being 40 revolvable whereby to cause ice deposited in the cylinder to be revolved over the sharpened edge of the blade as it travels longitudinally downwardly over the blade, and a helical blade formed on the exterior surface of the cone for assisting in revolving the ice and forcing the same downwardly over the cutting edge of the blade.

2. A machine of the character described comprising a cylinder, a hopper formed at the upper end of the cylinder and into which pieces of ice may be deposited, said cylinder having a vertical slot formed in the wall thereof, a cone arranged concentrically of the cylinder in alignment with the slot, a vertical blade secured to the cylinder at one side of the slot and having a sharpened edge projecting into the cylinder, said cone being revolvable whereby to cause ice deposited in the cylinder to be revolved over the sharpened edge of the blade as it travels longitudinally

downwardly over the blade, a helical blade formed on the exterior surface of the cone for assisting in revolving the ice and forcing the same downwardly over the cutting edge of the blade, a dispensing cylinder formed on the cylinder in alignment with the slot, said slot forming a communication between the interior of the cylinder and the interior of the dispensing cylinder, and a plunger reciprocal in said dispensing cylinder.

3. A machine of the character described comprising a cylinder having a slot formed in the wall thereof, a blade at one side of said slot and having an edge projecting into the cylinder, a revolvable cone arranged within the cylinder and having a helical blade formed thereon whereby revolution of the cone will cause ice fed to the cylinder to be revolved over the blade as it passes the cylinder.

4. A machine of the character described comprising a vertically arranged cylinder, said cylinder having a vertical slot formed in the wall thereof, a vertically arranged blade at one side of said slot and having a sharpened edge projecting into the cylinder, a revolvable cone arranged within the cylinder concentrically thereof, said cone having a helical blade formed thereon whereby revolution of the cone will cause ice fed to the cylinder to be revolved over the blade as it travels downwardly in the cylinder.
